UNITED STATES PATENT OFFICE.

GEORGE E. SMITH, OF CHICAGO, ILLINOIS.

DESIGN FOR AN AQUARIUM-FRAME.

Specification forming part of Design No. 6,887, dated September 16, 1873; application filed August 4, 1873.
[Term of Patent 3½ years.]

To all whom it may concern:

Be it known that I, GEORGE E. SMITH, of Chicago, in the county of Cook and State of Illinois, have invented a new and Improved Design for Aquarium-Frame, of which the following is a specification:

The nature of my design is fully represented in the accompanying photographic illustration, to which reference is made.

A is the aquarium-frame. b is the base; c, the columns; d, the top. Above the base-molding e is the frieze f, which is ornamented by intersecting serpentine lines g. h is the cornice or cap molding of the base. Each of the columns c has a pedestal, i. The outsides of the columns c represent twisted work. The top frame d, which connects the columns, is ornamented by a succession of ribs and grooves.

On each of the corners of the frame and over the columns is the figure of a spread-eagle, k.

I do not desire to be confined to the particular style of ornamentation described for the base, columns, or top. The distinctive features of my design are the ornamented base, the ornamented columns standing on pedestals, and the figure of the spread-eagle on each corner of the frame.

I claim as my invention—

The design for an aquarium-frame consisting of the base e f h, the columns c, standing on pedestals, and the eagles k, as shown and described.

GEORGE E. SMITH.
